UNITED STATES PATENT OFFICE.

LOUIS McCUTCHON, OF HAVANA, CUBA.

DESIGN FOR A GARTER-HOOK.

SPECIFICATION forming part of Design No. 35,298, dated November 19, 1901.

Application filed October 12, 1901. Serial No. 78,500. Term of patent 14 years.

To all whom it may concern:

Be it known that I, LOUIS McCUTCHON, a citizen of the United States, and a resident of Havana, in the Province of La Habana, in the Island of Cuba, have invented and produced a new and original Design for a Garter-Hook, of which the following is a specification, reference being had to the accompanying drawing, forming part thereof, in which the figure 10 is a perspective view of a garter-hook showing my design.

The leading feature of the design consists in the configuration of the garter-hook made the subject-matter of the accompanying illustration.

The design in its entirety consists of a shank A, terminating at its upper end in an overhanging head B and at its lower end in a hook C, appearing at its free end with an outwardly-extending and downwardly-curved

arm D, spaced from the lower edge of the head B, the said shank and hook appearing in serpentine shape and forming a correspondingly-shaped slot E between them, the said slot having its lower end extending approximately in alinement with the middle portion of the head B and at right angles to a slot B' in the head B.

Having described my invention, what I claim as new, and desire to secure by Letters Patent, is—

The design for a garter-hook, as herein shown and described.

In testimony whereof I have signed my name to this specification in the presence of two subscribing witnesses.

LOUIS McCUTCHON.
